[57] CLAIM

The ornamental design for a holder for oxygenator bottle, as shown and described.

DESCRIPTION

FIG. 1 is a perspective view of a holder for oxygenator bottle, showing my new design;

FIG 2 is a front elevational view, the rear elevational view being substantially a mirror image, thereof;

FIG. 3 is an elevational view of one side, thereof;

FIG. 4 is an elevational view of the other side, thereof;

FIG. 5 is a top plan view; thereof;

FIG. 6 is a bottom plan view, thereof; and,

FIG. 7 is an elevational view, as in FIG. 3, but including in broken line the outline of an oxygenator bottle forming no part of the claimed invention and included solely for illustrative purposes.

FIG. 1.

FIG. 2.

FIG. 5.

FIG. 3.

FIG. 4.

FIG. 6.

FIG. 7.
